DISPENSING CLOSURE

Roy B. Steidley, Costa Mesa, Calif., assignor to RDW
Industries, Inc., Santa Ana, Calif.

Filed Jan. 20, 1971, Ser. No. 108,244

Term of patent 14 years

Int. Cl. D9—07

U.S. Cl. D9—258

FIG. 1

FIG. 2

FIG. 3

FIG. 4

FIG. 5

FIG. 6

FIG. 7

FIG. 1 is a perspective view of a dispensing closure showing my new design, said closure being in a closed or non-dispensing condition;

FIG. 2 is a view similar to FIG. 1, but with the closure arranged in its dispensing condition;

FIG. 3 is a side elevation of the closure in its non-dispensing condition;

FIG. 4 is a front elevation thereof;

FIG. 5 is a rear elevation thereof.

FIG. 6 is a top plan view thereof; and
FIG. 7 is a bottom plan thereof.

I claim:

The ornamental design for a dispensing closure, as shown.
